CLAIM

The ornamental design for a plant acclimatizing box, as shown and described.

DESCRIPTION

FIG. 1 is a perspective view of a plant acclimatizing box;

FIG. 2 is a front side elevation view thereof;

FIG. 3 is a back side elevation view thereof;

FIG. 4 is a right side elevation view thereof;

FIG. 5 is a left side elevation view thereof;

FIG. 6 is a top plan view of thereof; and,

FIG. 7 is a top view of thereof, with top portion removed in order to illustrate internal design.

The broken lines depict environmental subject matter only and form no part of the claimed design.
